UNITED STATES PATENT OFFICE.

NORBERT J. SCHELL, OF BEAVER FALLS, PENNSYLVANIA.

RAIL-ANCHOR.

1,180,082.

Specification of Letters Patent. Patented Apr. 18, 1916.

Application filed December 9, 1915. Serial No. 65,897.

To all whom it may concern:

Be it known that I, NORBERT J. SCHELL, a citizen of the United States, and a resident of Beaver Falls, in the county of Beaver 5 and State of Pennsylvania, have invented a new and useful Improvement in Rail Anchors, of which the following is a specification.

One of the objects of my invention is to 10 provide an anchor, comprising two interlocking rail gripping members adapted to coöperate with a tie to prevent the creeping of the rails, which, owing to the peculiar construction of engaging tongue and groove 15 formed upon the interlocking rail engaging members, will more firmly grip the rail as it tends to creep or slide, but in which the original gripping position of the members upon the rail base will not be changed by 20 such tightening.

A further object of my invention is to provide a rail anchor in which the rail engaging members are connected by a tongue and groove construction, which will fit 25 snugly at all times, and so prevent the accumulation of dirt and water in the groove.

A still further object of my invention is to provide an anchor in which all unnecessary metal is eliminated, but which will be of 30 strong and durable construction, and which will be positively braced in all directions.

With these and other objects in view which will become apparent as the description proceeds, my invention resides in the 35 construction and arrangement of parts to be hereinafter described and claimed, and illustrated in the accompanying drawings forming a part of this specification and in which like reference characters indicate like parts throughout the several views.

Figure 1 is an end view of the anchor in position upon a rail. Fig. 2 is a vertical section on line 2—2 of Fig. 3 looking in the direction of the arrows. Fig. 3 is a top plan 45 view of the anchor and rail with a portion of the tie against which the anchor abuts. Fig. 4 is a perspective view of the locking rail engaging member. Fig. 5 is a top plan 50 view of the rail engaging member which carries the tie abutting plate.

Referring to the drawings, a rail and tie

of standard construction are shown at A and B respectively.

My improved rail anchor comprises the member C which abuts against the tie, and 55 the locking member D, each preferably formed of an integral piece of malleable iron.

The member C comprises a base 1 having 60 downwardly extending strengthening flanges 9 on its sides, fitting against the lower side of the base of the rail and tapering in width from its end beneath the rail base to its outer end where it is formed into a rail gripping hook 2, curving upwardly over the edge of 65 the base of the rail. A downwardly projecting curved tongue 3 is formed upon the end of the base 1 opposite the rail engaging hook. This tongue is an arc of a circle 70 whose center does not coincide with the center of the rail engaging hook, but is at the edge of the hook farther from the tie against which the anchor abuts, where it passes beneath the rail base. The abutment resting 75 against the tie, consists of the abutting plate 5, which extends a slight distance beyond the side of the rail opposite the rail engaging hook, and a downwardly and outwardly extending brace 6 formed therewith, joined at its upper end to the lower side of the base 1. 80 The abutting plate is further strengthened by a diagonal brace 7 extending upwardly from the lower outside corner of the abutting plate, to the brace 6 from the opposite side of which a continuation 8 of the brace 7, 85 extends to the side of the base 1 near the rail engaging hook.

The locking rail gripper coöperating with the above described member, comprises a base 10, of less width than the length of the 90 tongue 3, and having downwardly extending flanges 11 on its sides, fitting against the lower side of the rail base and having a rail gripping hook 12 formed on its outer end, the hook 12 being relatively wider than 95 the hook 2. A groove 13 which is an arc of the same circle as the tongue 3, is formed in the base 10 and coöperates with the tongue to lock the two members upon the rail.

In operation the two members are locked 100 upon a rail with the abutting plate back of a tie relative to the direction of the creeping

tendency of the rail. The center of the circle from which the tongue and groove are described, being back of the center of the hook 2, relative to the tie, will cause the 5 locking member D to lie back of the center of the hook 2 when the anchor is locked to the rail. When the rail has a tendency to creep, the pressure against the abutting plate will cause the tongue to slide in the groove 10 and rotate the member C about the point forming the center of the arcs of the tongue and groove, and thus exert a direct side pull upon the member D, diminishing the distance between the said engaging hooks and 15 thus causing the anchor to grip the rail more securely. It will also be observed that since the tie abutting member carries the downwardly projecting tongue, pressure upon this member will cause the tongue and 20 groove to coöperate more securely, thus preventing the two parts from becoming loosened and sagging away from the rail base. It will be observed further that when the anchor is in position upon a rail, the 25 member D cannot move in either direction independent of the member C, and the anchor cannot be removed from the rail until the tongue is slid entirely out of the groove. It will therefore be seen that I have 30 provided a rail anchor which will grip the rail more securely when it has a tendency to creep, and which will at all times fit snugly and securely upon the rail, leaving no opening for the collection of dirt or water.

35 I claim:—

1. A rail anchor comprising coöperating rail gripping members, one of the said members having a base formed with strengthening flanges on its sides, tapering in width to 40 a relatively narrow rail gripping hook on its outer end, the other end of the said base having a downwardly extending curved tongue which is an arc of a circle whose center is at the edge of the above mentioned rail gripping hook farthest away from the rail tie against which the anchor abuts, a downwardly and outwardly extending member on the lower side of the said base formed with an abutting plate on its outer end adapted to bear 45 against a tie, a diagonal brace for the said abutting plate extending from the lower outer edge of the abutting plate to the above mentioned outwardly and downwardly extending member, a continuation of the said brace extending from the other side of the said downwardly extending member to the said rail gripping plate adjacent its end opposite the said abutting plate.

2. A rail anchor comprising interlocking rail gripping members, a tie abutting plate formed on one of the said members beneath the edge of the rail engaged by the other member, the first mentioned member having a tongue formed thereon, the other member having a groove formed therein coöperating with the said tongue to lock the gripping members upon the rail, the said tongue and groove being arcs of a circle whose center is upon the edge of the gripping member carrying the tie abutting plate diagonally opposite the said plate.

3. A rail anchor comprising rail gripping members extending from each side of the rail base beneath the same, and having means upon their ends beneath the said base coöperating to lock the said members upon a rail, one of the said members being formed to contact with a tie and being adapted, when pressure is applied thereto at the point of contact with a tie, to swing with a point diagonally opposite the said point of contact as a pivot, to exert a lateral pull upon the other member and so cause the gripping members to more firmly grip the rail.

4. A rail anchor comprising rail gripping members having concentrically curved inter-

groove which is an arc of the same circle as 65 the above mentioned tongue, and adapted to coöperate therewith to lock the gripping members to the rail.

2. A rail anchor comprising coöperating rail gripping members, one of the said members having a tie abutting plate formed therewith and tapering in width to a relatively narrow rail gripping hook at its outer end, the other end of the said base having a downwardly extending curved tongue which 70 is an arc of a circle whose center is at the edge of the above mentioned rail gripping hook farthest away from the rail tie against which the anchor abuts, the other rail gripping member having a rail gripping hook 75 on its outer end, and the other end of the said member having a groove which is an arc of the same circle as the above mentioned tongue, and adapted to coöperate therewith to lock the gripping members to 80 the rail.

3. A rail anchor comprising coöperating rail gripping plates, a downwardly and outwardly extending member on the lower side of one of the plates formed with an abutting 90 plate on its outer end adapted to bear against a tie, a diagonal brace for the said abutting plate extending from the lower outer edge of the abutting plate to the above mentioned outwardly and downwardly extending member, a continuation of the said brace extending from the other side of the said downwardly extending member to the said rail gripping plate adjacent its end opposite the said abutting plate.

4. A rail anchor comprising interlocking rail gripping members, a tie abutting plate formed on one of the said members beneath the edge of the rail engaged by the other member, the first mentioned member having a tongue formed thereon, the other member having a groove formed therein coöperating with the said tongue to lock the gripping members upon the rail, the said tongue and groove being arcs of a circle whose center is upon the edge of the gripping member carrying the tie abutting plate diagonally opposite the said plate.

5. A rail anchor comprising rail gripping members extending from each side of the rail base beneath the same, and having means upon their ends beneath the said base coöperating to lock the said members upon a rail, one of the said members being formed to contact with a tie and being adapted, when pressure is applied thereto at the point of contact with a tie, to swing with a point diagonally opposite the said point of contact as a pivot, to exert a lateral pull upon the other member and so cause the gripping members to more firmly grip the rail.

6. A rail anchor comprising rail gripping members having concentrically curved inter-

locking members coöperating to lock the said rail gripping members upon a rail, one of the said rail gripping members having an abutment adapted to bear against a tie, the said coöperating locking members being so curved as to cause the said rail gripping member, when pressure is placed upon the said abutment, to swing with a point

diagonally opposite the said abutment as a pivot, to exert a lateral pull upon the other rail gripping member and so cause the gripping members to more firmly grip the rail.
